UNITED STATES PATENT OFFICE.

CHESTER H. BRASELTON, OF DETROIT, MICHIGAN, AND FRED M. CARROLL, OF NEW YORK, N. Y., ASSIGNEES TO WOLVERINE SPARK PLUG COMPANY, INC., OF DETROIT, MICHIGAN, A CORPORATION OF NEW YORK, (INCORPORATED IN 1916.)

SPARK-PLUG.

1,269,783.

Specification of Letters Patent. Patented June 18, 1918.

Original application filed August 17, 1914, Serial No. 857,113. Divided and this application filed August 18, 1918. Serial No. 115,578.

To all whom it may concern:

Be it known that we, CHESTER H. BRASELTON and FRED M. CARROLL, citizens of the United States, residing at Detroit, in the county of Wayne and State of Michigan, and New York, county of New York, and State of New York, have invented certain new and useful Improvements in Spark-Plugs, of which the following is a specification.

This invention relates to spark plugs for internal combustion engines and more particularly to spark plugs of the quickly detachable type in which the insulator is removable without the use of a wrench or other tool. This application is filed as a division of our pending application, Serial No. 857,113, filed August 17th, 1914.

The principal object of this invention was to provide such connections between the insulator and the member in which it is to seat and such fastening means for locking the insulator to its seat as to permit of the quick detachment and removal of the insulator without the use of any tools. Another object of our invention was to provide means which, while permitting the quick removal and detachment of the insulator, lock the insulator effectively in place in its seat, forming an efficient gas-tight joint between the insulator and the member in which it seats so as to prevent leakage of gas from the engine cylinder when under compression. Still another object of our invention was to provide fastening means of a somewhat yielding or resilient nature so as to yield somewhat, in service, to take up the variations in the different parts which may occur in making them in quantities while, at the same time, locking the insulator effectively to its seat.

Further objects, and objects relating to economies of manufacture and details of construction, will definitely appear from the detailed description to follow.

We accomplish the objects of our invention by the devices and means described in the following specification. The invention is clearly defined and pointed out in the 50 claims.

Structures constituting preferred embodiments of our invention are clearly illus-

trated in the accompanying drawings, forming a part of this specification, in which:

Figure I is a view, partly in section and partly in elevation, of one form of our invention.

Fig. II is a view, partly in section and partly in elevation, showing the separate sleeve of Fig. I with the fastening member attached.

Fig. III is a perspective view of the bushing.

Fig. IV is a view of another form of plug, showing it half in section and half in elevation.

Fig. V is a view, partly in section, of another form of plug in which the fastening member engages an annular shoulder on the insulator.

Fig. VI is a view of a modified form of fastening member.

Fig. VII is a sectional view on the line 7-7 of Fig. VI.

In the drawings, similar reference characters refer to similar parts throughout the several views and the sectional views are taken looking in the direction of the little arrows at the ends of the section lines.

Considering the numbered parts of the drawing, the bushing 1 has a lower externally threaded portion 2 and an upper portion 3 which is preferably of non-circular cross section so as to receive a wrench or similar tool. The bushing has an axial opening therethrough in which the spark plug insulator is disposed and an internal upwardly facing shoulder 4 on which the external, downwardly facing shoulder 5 of the insulator seats. At diametrically opposite points in the upper portion 3 of the bushing, there are provided L-shaped slots 6, the upper edge of the horizontal parts of said slots being inclined downwardly from the vertical portions for a purpose which will appear hereinafter.

The insulator 7 has the external, downwardly facing shoulder 5, already mentioned, and, above the latter, the upwardly-facing shoulder 8. The ring 9 is disposed around the insulator 7 resting on the shoulder 8, the outer diameter of the ring 9 being preferably the same as that of the portion of the insulator between shoulders 5 and 8,

so that the ring is disposed between the body of the insulator and the upper part of the bushing. The ring 9 has at its upper edge a thin flange or fin 10 which may be crimped or spun on to the body of the insulator to fasten the ring thereto. The fastening member or bail 11, has the inwardly turned bearing portions 12 and the offset or eccentric portions 13. Diametrically opposite openings 14 are provided in the ring 9, said openings being preferably counterbored and receiving the eccentric portions 13 of the bail. When the parts are assembled together, the bearing portions 12 of the bail have bearings in the horizontal parts of the slots 6, fulcruming against the upper wall of this part of the slot. Since this upper wall is inclined, by fulcruming the bearing portions against different parts thereof, the fastening member will have its bearings at different vertical distances above the seat in the bushing. This provides for the slight variance in parts which may occur in manufacture.

25 The insulator 7 preferably carries both electrodes, the central electrode 15 extending longitudinally through the insulator and connecting with the terminal cap at the upper end. The second electrode 16 extends from the lower end of the insulator, at one side of the center, to the shoulder 8 where it makes electrical connection with the ring 9 and through said ring and the fastening member 11 with the bushing.

35 In Fig. IV, we have shown another form of our invention in which the insulator 7 has a peripheral groove 17, at diametrically opposite points in the bottom of which are provided the openings 18 in which are inserted the sleeves 19. The eccentric cam portions 13 of the fastening member 11 are disposed in said sleeves and the bearing portions 12 fulcrum in the slots in the bushing, as in the previously described form, and, 40 when the fastening member is rotated, the cam portions exert pressure on the insulator, through the intermediate sleeves 19, to lock the insulator to its seat. The second electrode 16 extends upwardly from the 45 lower end of the insulator and makes electrical connection with one of the sleeves 19 and, through the sleeve 19 and the fastening member 11, with the bushing.

50 In Fig. V, we have shown another form of our invention in which the ring 9 is omitted and the offset cam portions 13 of the bail 11 act directly on the annular upwardly-facing shoulder 8 of the insulator. In this form, the bail 11 is not carried by 55 the insulator but in removing the insulator the bail is removed independently. In this form, we have shown the second electrode 29 carried by the lower edge of the bushing. This electrode might be carried by the electrode, in this form as well as in the other

forms, in which case the upper end of the electrode would be so located as to make electrical connection with the bushing or the bail 11.

In Figs. VI and VII, we have shown a slightly modified form of fastening member. The fastening member 21 is made of stock of elliptical cross section and the inwardly-turned portions 22 are twisted through an angle of about forty-five degrees so that the major axis of the elliptical cross-section stands at an angle of about forty-five degrees to the body of the bail 21. The action of the twisted portions is similar to the action of the eccentric portions shown in the other forms and, when the bail is rotated, the insulator is cammed to its seat.

In all of these forms, we preferably make the bail or fastening member of spring stock and, since there is a substantial space between the fulcrum points and the bearing points on the intermediate ring or sleeve, or the insulator in Fig. V, the fastening member will exert a yielding pressure to yieldingly force the insulator to its seat. This serves to take up the slight variations in the dimensions of parts and the slight inaccuracies in the seat which may sometimes occur in manufacture. It also serves to prevent injury to the insulator due to the use of too much force in rotating the bail. It is also worthy of note that the bail works with an increasing mechanical advantage due to the resilient nature of the stock used.

From the description of the parts given above, the operation should be very readily understood. In the form shown in Figs. I and II, the insulator 7, carrying the ring 9 and the bail 11, with the bail in a substantially vertical position, is inserted in the axial opening in the bushing until the insulator rests on its seat in the bushing. The bearing portions 12 of the bail enter the vertical portions of the slots 6 and a slight turn is then given to the insulator bringing the portions 12 of the bail into the horizontal portions of the slots 6. The fastening member 11 is then rotated through substantially 135° and, since the bearing portions 12 fulcrum in the slot, the eccentric portions 13, which are disposed in the openings 14 in the ring 9, exert a yielding pressure on the ring, and through the ring on the insulator, to lock the insulator to its seat.

The operation of the form shown in Fig. IV is the same except that the fastening member acts on the insulator through the sleeves 19 instead of through the ring 9.

In the form shown in Fig. V, the operation is similar but the bail acts directly on the annular upwardly-facing shoulder 8. In this form, the bail is removable independently of the insulator since it is not carried thereby.

In the forms shown in Figs. I and II, the

bail is normally removable with the insulator but, since it is made from spring stock, the inwardly-turned ends may be sprung apart sufficiently to remove them from the openings 14 in the ring 9.

Similarly, in the form shown in Fig. IV, the ends of the bail can be removed from the sleeves 19.

We have shown the insulator seating in a bushing adapted to screw into an engine casing but this is not essential to our invention as the insulator might seat in any relatively fixed member provided that relatively fixed bearings are provided for the bail. 10 For instance, the insulator might seat directly in the engine casing.

In the forms shown in Figs. I to IV, the bail does not exert pressure directly on the insulator but acts through an intermediate member or members. In Fig. I, this intermediate member is the ring 9 and, in Fig. IV, the intermediate members are the sleeves 19. I have shown the ring 9 as secured to the insulator by crimping or spinning it thereon but this is not absolutely essential as the ring may simply rest on the upwardly-facing shoulder 8. In the forms shown in Figs. I, II and V, the bail 11 acts on an annular upwardly-facing shoulder on 20 the insulator. In Fig. I, the bail acts through the ring 9 while, in Fig. V, it acts directly on the shoulder.

We are aware that the particular embodiments of our invention are susceptible of considerable variation without departing from the spirit of our invention and, therefore, we do not wish to be limited to these embodiments except as required by the appended claims.

Having thus described our invention, what we claim as new, and desire to secure by Letters Patents, is:

1. In a spark plug, the combination of a bushing, provided with diametrically opposite L-shaped slots, the upper walls of the horizontal portions of said slots being downwardly inclined; an electrode carrying insulator adapted to removably seat in said bushing, said insulator having an annular upwardly-facing shoulder; a ring resting on said shoulder; and a resilient fastening member straddling said plug and having inwardly turned ends, adapted to have bearings in said slots, and eccentric portions disposed in diametrically opposite openings in said ring.

2. In a spark plug, the combination of a bushing, provided with diametrically opposite L-shaped slots; an electrode carrying insulator adapted to removably seat in said bushing, said insulator having an annular upwardly-facing shoulder; a ring resting on said shoulder; and a resilient fastening member straddling said plug and having inwardly turned ends, adapted to have bear-

ings in said slots, and eccentric portions disposed in diametrically opposite openings in said ring.

3. In a spark plug, the combination of a bushing, provided with diametrically opposite L-shaped slots; an electrode-carrying insulator adapted to removably seat in said bushing; a ring carried by said bushing and provided with diametrically opposite openings; and a resilient fastening member having inwardly turned ends adapted to bear in said slots and eccentric portions disposed in the openings in said ring, said fastening member being rotatable whereby a yielding pressure will be exerted on said insulator through said ring to lock the insulator to its seat.

4. In a spark plug, the combination of a bushing, provided with diametrically opposite L-shaped slots; an electrode-carrying insulator adapted to removably seat therein and provided with an annular, upwardly-facing-shoulder; and a resilient, rotatable fastening member having inwardly turned ends adapted to bear in said slots and eccentric portions adapted to exert a yielding pressure on said shoulder on the insulator to lock it to its seat when the fastening member is rotated.

5. In a spark plug, the combination of a relatively fixed member; an electrode-carrying insulator adapted to removably seat therein; and a rotatable fastening member having inwardly-turned ends adapted to bear on said fixed member, said fastening member being of non-circular cross-section and the ends of said member being twisted, said twisted portions being adapted to exert pressure on the insulator to lock it to its seat when the fastening member is rotated.

6. In a spark plug, the combination of a bushing; an electrode-carrying insulator adapted to removably seat therein; an intermediate member adapted to engage the insulator; and a fastening member having alined, inwardly-turned ends for co-operating with the bushing and the intermediate member to fasten the insulator to its seat in the bushing when the fastening member is rotated about the axis of the inwardly-turned portions.

7. In a spark plug, the combination of a bushing; an electrode-carrying insulator adapted to removably seat therein; an intermediate member adapted to engage the insulator; and a fastening member having alined, inwardly turned ends, a portion of said ends being farther from the axis of rotation of the fastening member than are other portions whereby, when the fastening member is rotated about the axis of the inwardly-turned ends with such portions in co-operation with the bushing and the intermediate member, the insulator will be forced to its seat in the bushing.

8. In a spark plug, the combination of a bushing; an electrode-carrying insulator adapted to removably seat therein; an intermediate member adapted to transmit pressure to said insulator; and a fastening member having a plurality of projections extending over portions of said intermediate member and adapted, when the fastening member is rotated about bearing surfaces on the bushing and about an axis at an angle to the longitudinal axis of the plug, to force the insulator against its seat in the bushing.

9. In a spark plug, the combination of a bushing; an electrode-carrying insulator adapted to removably seat therein; an intermediate member adapted to transmit pressure to said insulator; and a fastening member having a plurality of projections extending over portions of said intermediate member and adapted, when the fastening member is rotated about a plurality of diametrically opposite bearing surfaces on the bushing and about an axis at an angle to the longitudinal axis of the plug, to force the insulator against its seat.

10. In a spark plug, the combination of a bushing; an electrode-carrying insulator adapted to removably seat therein; an intermediate member adapted to transmit pressure to said insulator; and a fastening member having separated portions adapted to project between the bushing and the intermediate member at peripherally separated points, said portions being so constructed that rotation of the fastening member about an axis at an angle to the longitudinal axis of the plug will cause relative movement between the intermediate member and the bushing to force the insulator against its seat in the bushing.

11. In a spark plug, the combination of a hollow bushing having an internal seat and provided with peripherally separated bearing surfaces, points of which are greater distances from said seat than are other points; an electrode-carrying insulator adapted to removably seat in said bushing; an intermediate member adapted to transmit pressure to said insulator; and a fastening member provided with inwardly-turned ends, portions of which are adapted to bear upon the said bearing surfaces in the bushing and other portions of which are adapted to project over and bear upon the intermediate member to force the insulator to its seat in the bushing when the fastening member is rotated about the inwardly turned ends.

12. In a spark plug, the combination of a bushing; an electrode-carrying insulator adapted to removably seat therein; an intermediate member adapted to transmit pressure to said insulator; and a yielding fastening member having separated portions adapted to project between the bushing and the

intermediate member at peripherally separated points, said portions being so constructed that rotation of the fastening member about an axis at an angle to the longitudinal axis of the plug will cause relative movement between the insulator and intermediate member to force the insulator against its seat in the bushing.

13. In a spark plug, the combination of an electrode-carrying insulator; a bushing having bearing openings and a seat for the insulator; an intermediate member adapted to transmit pressure to the insulator, and a fastening member having inwardly turned yielding ends coöperating with the bearing openings and the intermediate member for attaching the insulator to the seat in the bushing when the ends are rotated by movement of the fastening member.

14. In a spark plug, the combination of an insulator; a bushing having diametrically opposite bearings and an internal seat for the insulator; an intermediate member adapted to transmit pressure to said insulator; and a fastening member comprising two portions to be interposed between the bearings and the intermediate member and then rotated by movement of the fastening member, said portions being so constructed as when rotated to yieldingly hold the insulator against its seat.

15. In a spark plug, the combination of an electrode-carrying insulator; a bushing having diametrically opposite bearing openings and an internal seat for the insulator; an intermediate member adapted to transmit pressure to the insulator; and a fastening member having inwardly-turned ends rotatable in the aforesaid bearings and formed to coöperate with the intermediate member to yieldingly hold the insulator against its seat in the bushing when the fastening member is moved to a certain position.

16. In a spark plug, the combination of a relatively fixed member having a seat and an opening; an electrode-carrying insulator adapted to pass into the opening and against the seat; an intermediate member adapted to transmit pressure to the insulator; and a single, manipulatively operable, yielding pressure applying element coöperating with the intermediate member to force the insulator against its seat in the fixed member and hold it there in opposition to pressure exerted from the engine chamber when the plug is in use in the same.

17. A spark plug comprising a fixed member having an opening and a seat for an insulator; an electrode-carrying insulator adapted to pass into the opening and against the seat; an intermediate member adapted to transmit pressure to said insulator; and a fastening member manually operable to exert a yielding pressure on said intermediate member.

ate member to force the insulator against its seat in the fixed member.

18. In a spark plug, the combination of a bushing; an electrode-carrying insulator adapted to seat therein; an intermediate member adapted to transmit pressure to said insulator; and a rotatable, yielding, pressure applying means adapted to rotate about an axis at an angle to the longitudinal axis 10 of the insulator in coöperation with the intermediate member and the bushing to force the insulator to its seat in the bushing.

19. In a spark plug, the combination of a bushing; an electrode-carrying insulator 15 adapted to removably seat therein; an intermediate member adapted to transmit pressure to said insulator; and a rotatable, resilient member coöperating with the intermediate member and the bushing and rotatable about an axis at an angle to the longitudinal axis of the insulator and on a line 20 that will pass through the projected transverse area of the insulator, said resilient member serving when rotated to force the 25 insulator against its seat.

20. In a spark plug, the combination of a bushing; an electrode-carrying insulator adapted to removably seat therein; an intermediate member adapted to transmit pressure 30 sure to said insulator; and a crank-like resilient member rotatably engaging with the bushing and intermediate member and serving, when rotated, to force the insulator against its seat and hold it there by reason 35 of the crank-like member assuming a substantially "dead center" relationship between the intermediate member and the bushing.

21. In a spark plug, the combination of a 40 bushing; an electrode-carrying insulator adapted to removably seat therein; an intermediate member adapted to transmit pressure to said insulator; and a resilient member rotatable about an axis at an angle to 45 the axis of the plug and fulcruming against the bushing and acting against the intermediate member in substantially alining but oppositely directed lines of action passing through points close to the fulcrum point, whereby the moment of force tending to rotate the rotatable member will be too small to overcome the frictional resistance against the resilient rotatable member.

22. In a spark plug, the combination of a 50 bushing; an electrode-carrying insulator adapted to removably seat therein; an intermediate member adapted to transmit pressure to said insulator; and a cam-like, yield-

ing fastening member adapted to be rotated to apply a gradually increasing yielding pressure to the intermediate member to force the insulator against its seat.

23. In a spark plug, the combination of a bushing; an electrode-carrying insulator adapted to removably seat therein; an intermediate member adapted to transmit pressure to said insulator; and a yielding, fastening means engaging said intermediate member and manually manipulative to apply a yielding pressure to force the insulator 70 against its seat.

24. In a spark plug, the combination of a relatively fixed member; an electrode-carrying insulator adapted to removably seat therein; an intermediate member adapted to transmit pressure to said insulator; and an element carried by said intermediate member and movable therewith into coöperative relationship with said fixed member and adapted to be rotated about an axis transverse to the axis of the insulator to apply pressure to lock it to its seat.

25. In a spark plug, the combination of a relatively fixed member; an electrode-carrying insulator adapted to removably seat therein; an intermediate member adapted to transmit pressure to said insulator; and a single element, comprising a plurality of separated portions connected by operating means, and rotatable about an axis transverse to the axis of the insulator to apply pressure to the intermediate member to lock the insulator to its seat.

26. In a spark plug, the combination of a relatively fixed member; an electrode-carrying insulator adapted to removably seat therein; an intermediate member adapted to transmit pressure to said insulator; and a single element rotatable about an axis transverse to the axis of the insulator to apply a yielding pressure to the intermediate member to lock the insulator to its seat.

27. In a spark plug, the combination of a relatively fixed member; an electrode-carrying insulator adapted to removably seat therein; an intermediate member adapted to transmit pressure to said insulator; and an element rotatable about an axis transverse to the axis of the insulator and operable with an increasing mechanical advantage to apply pressure to said intermediate member to lock the insulator to its seat.

In witness whereof, we have hereunto set our hands:

CHESTER H. BRASELTON
FRED M. CARROLL.
